UNITED STATES PATENT OFFICE.

PETER SPECK, OF ST. LOUIS, MISSOURI.

TRUSS.

Application filed January 11, 1923. Serial No. 612,020.

To all whom it may concern:

Be it known that I, PETER SPECK, a citizen of the United States, and a resident of the city of St. Louis and State of Missouri,

5 have invented a new and useful Truss, of which the following is a specification.

This invention relates to trusses.

An object of the invention is to provide an improved truss for use in cases of rupture or hernia and comprising a novel and improved aluminum pad including a cup portion of improved design for supporting and retaining the rupture or hernia in proper position to afford relief to the user.

10 Another object of the invention is to provide an improved aluminum truss pad having an oval concavity in its body contacting side surrounded by an oval rim, and means for supporting the device in position on the 15 user so that the major axis of the device is substantially vertical in order to obtain better results from the use of the device.

Other objects will appear from the following description, reference being made to the 20 drawing in which

Fig. 1 is a view showing the complete truss.

Fig. 2 is a relatively enlarged view showing the inner dished side of the oval aluminum pad.

Fig. 3 is a vertical sectional view on the line 3—3 of Fig. 2.

In the embodiment of the invention shown the pad comprises an aluminum body 1 having an approximately oval concavity or dished recess 2 formed in its inner side in such arrangement that when the device is in use the major axis of the oval concavity or recess is approximately vertical. A relatively wide oval rim or flange 3 surrounds the concavity or recess 2 and is formed with a wide flat surface or face 4 adapted to press against the body of the user. The marginal corner 5 of the flange 3 is rounded so that it will not cut or hurt the user. As will be seen by reference to Fig. 3 the wall of the concavity or recess 2 intersects the flat surface 4 with a rounded portion 6.

50 A slot 7 is formed through the body 1 between the recess 2 and the outer side of said body. The slot 7 extends transversely of the major axis of the device and is designed and adapted to receive a belt 8 by which the device is supported on the wearer and 55 pressed against the body of the wearer with the major axis of the oval transversely ver-

tical. The aluminum cup pad is slidable on the belt 8 and may be accurately adjusted to proper position to obtain the most beneficial results.

As shown a strap 9 has loops 10 through which the belt 8 passes. Said strap is provided for the purpose of holding the belt down to proper position on the wearer so that the aluminum cup pad cannot slip or 60 work away from its proper adjustment.

I have actually used this device with more satisfaction and more beneficial results than I have been able to obtain from any devices at present on the market or available so far 65 as I have been able to discover. I have found in my own case that the rigid and inflexible aluminum cup pad affords relief where resilient or elastic pads have only aggravated the affliction. The aluminum cup 70 pad being rigid and imperforate retains its position better than a pad having air vents or openings. It is therefore a fact that the invention obtains more beneficial results than I have been able to obtain elsewhere 75 or by use of other devices. It may be that the construction and arrangement may be varied somewhat without disadvantage, although I prefer the exact construction shown and described for the reasons stated. How- 80 ever, I do not restrict myself unessentially, but what I claim and desire to secure by Letters Patent is:—

1. A truss pad, composed of an aluminum body having an open oval concavity in the 85 side that bears against the body of the wearer, and an oval flange surrounding said open concavity and having a comparatively wide surface to bear against the body of the wearer, and said aluminum body having a 90 slot therethrough transversely of the longitudinal axis of the open oval concavity.

2. A truss pad, composed of an aluminum body having an open oval concavity in the 95 side that bears against the body of the wearer, an oval flange surrounding said open concavity and having a comparatively wide surface to bear against the body of the wearer, said aluminum body having a slot therethrough transversely of the longitudinal axis of the open oval concavity, and a belt passing through said slot for supporting said aluminum body in position in which the major axis of the open oval concavity 100 is approximately vertical.

PETER SPECK.
